UNITED STATES PATENT OFFICE

ADOLPH BAYER, OF NEW YORK, N. Y.

GAS DETECTION APPARATUS

Application filed November 23, 1927. Serial No. 235,342.

The present invention is concerned with the provision of an electrically operated mechanism for detecting the presence of noxious combustible gases.

5 It may serve a wide range of utility in the arts, being peculiarly adapted for use in mines, grain elevators, and other locations where explosive gases are likely to accumulate.

10 It is also well suited for use in the home for purposes of detecting the presence of escaping gas.

The invention is based upon the fact that a platinum wire unlike other forms of electrical 15 conductors may become hot enough to ignite surrounding gases, and remain at such a heat over a long period of time without melting or disintegrating. I make use of this fact by providing a platinum fuse as part of an 20 alarm circuit. The fuse under normal air conditions will remain hot without melting or disintegrating. When noxious combustible gases are present however, they will burn on the surface of the fuse and increase its temperature to such an extent, that the fuse will melt and operate an alarm.

Objects of the invention are to provide a unique alarm circuit embodying a gas-sensitive fuse of this character, and to provide a 30 gas-sensitive fuse which may be used in various alarm circuits.

The fuse itself is of simple, practical construction, rugged, durable and efficient in use, and well suited to the requirements of economical manufacture and convenient installation.

With the above noted and other objects in view, the invention consists in certain novel features of construction and combinations 40 and arrangements of parts, as will be more fully hereinafter set forth and pointed out in the claims. The invention may be more fully understood from the following description in connection with the accompanying drawings, wherein—

Fig. 1 is a longitudinal sectional view through a fuse embodying the present invention.

Fig. 2 is a transverse sectional view therethrough on the line 2—2 of Fig. 1.

Fig. 3 is a wiring diagram showing the position of a fuse in an alarm circuit.

The fuse illustrated in detail in Figs. 1 and 2 consists of a pair of blocks 10 of insulating material spaced apart and rigidly 50 connected by a plurality of parallel rods or bars 11, the ends of the bars being preferably molded in the blocks 10. Terminal members 12 also preferably molded in the blocks are arranged in alignment at the longitudinal 55 axis of the blocks with both their inner and outer ends projecting from the blocks. The inner ends of the terminals 12 are connected by a platinum fuse wire 13, and the outer ends of the terminals are preferably in electrical 60 contact with brass caps 14 slipped over the ends of the insulating blocks. The space between the two blocks in which the fuse 13 and the exposed portions of the arms 11 are disposed, is preferably confined within a 65 sleeve 15 of fine gauge wire mesh. This wire is of a well known character, and is designed to prevent the combustion of gases within the screen from igniting gases exposed exteriorly 70 thereof.

In Fig. 3 I have shown a wiring diagram in which a coil 16 energized from any suitable source of alternating current, transmits energy to a secondary coil 17. A lead wire 18 from one side of the coil 17 branches into a 75 pair of leads 19 and 20. The lead wire 19 is connected to the winding 20a of a magnet coil, and thence through a lead 21 to one terminal 12 of the fuse 13. The second terminal 12 of the fuse is connected to the opposite end 80 of the coil 17 by a lead 22.

Conductor 20 passes through an alarm 23 from whence a lead wire 24 connects with a fixed contact 25. A spring held armature 26 coacting with the magnet 20a is connected at 85 90

one end by a conductor 27 to the lead wire 22. When the magnet 20^a is de-energized, the armature is spring-urged against the contact 25.

5 In this circuit, the normal flow of current from the coil 17 is through the conductors 18 and 19, magnet 20^a, conductor 21, fuse 13 and conductor 22. The normal flow energizing the magnet holds the armature out of contact with the terminal 25.

10

When the fuse 13 burns out due to the ignition of combustible gases on its surface, the above described circuit is broken, the magnet is de-energized, and the alarm circuit sounded when the armature contacts at 25.

20 By accurately predetermining the gauge of the fuse and the current passing therethrough, the fuse may always be maintained at a temperature sufficient to ignite combustible gases without any deterioration of the fuse. When gases filter through the screen 15 however, they will ignite on the hot surface of the fuse, and the fuse will burn out, sounding an alarm circuit.

25 Obviously, the fuse might be used in other types of alarm circuits. In fact, various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claims.

35 I claim:

40 1. A fuse for gas detection apparatus including a pair of spaced blocks of insulating material, terminals mounted therein, a platinum fuse connecting the terminals, a group of rods having the ends embedded in said blocks for holding the blocks in spaced relation and a flame resistant wire mesh cage cooperating with the blocks to house the fuse.

2. A fuse for gas detecting apparatus, including a pair of spaced insulating blocks, electrodes carried by said blocks, a platinum conductor electrically connecting said electrodes and a wire mesh surrounding part of each of said blocks and said platinum conductor, said mesh permitting gas to flow therethrough and preventing the passage of flame.

name.
3. A fuse for gas detecting apparatus, including a pair of spaced insulating blocks, electrodes carried by said blocks, a platinum conductor electrically connecting said electrodes, and a wire mesh flame resistant cage carried by said blocks and surrounding said conductor.

60 4. An electrical fuse operable in the presence of combustible gases to break an electric circuit comprising spaced blocks, means for securing said blocks in aligned spaced relation, a wire screen confining the space between said blocks and being adapted to per-

mit free passage of gas therethrough and to prevent passage of flame therefrom, and a platinum fuse wire between said blocks whereby passage of current therethrough will retain said fuse wire at a constant state of incandescency sufficient to ignite combustible gases, said wire being adapted to be burned in the presence of said gases when said gases have been ignited thereby, thus to break the circuit through the fuse wire. 70 75

Signed at New York in the county of New York and State of New York this 21st day of November A D 1927.

ADOLPH BAYER.
